MANUFACTURE AND PRODUCTION OF
TUBULAR BODIES FROM SOLUTIONS OF
CELLULOSE OR OF CELLULOSE COM-
POUNDS

7 Claims. (Cl. 18—15)

This invention relates to the manufacture and production of tubular bodies, particularly those intended for use as sausage casings, from solutions of cellulose or cellulose compounds such as 5 viscose and cuprammonium cellulose.

It is well known that tubular bodies can be produced by projecting viscose through an annular slot into a suitable bath. This bath can be acid, in which case the viscose is converted directly 10 into cellulose hydrate, or the bath may be alkaline or neutral, in which case a tube of cellulose xanthate is first formed and this is subsequently treated with acid to convert it into cellulose hydrate. It has hitherto been proposed to lead 15 the tube, immediately after its production, through a tank containing hardening fluid, the tube being passed under and over guides or guide wheels or rollers so that the tube follows a zig-zag path. It has also been proposed to supply air 20 under gentle pressure to inflate the tube until coagulation is complete.

We have now found that advantages are obtained if the tube, after leaving the bath in which it is formed, is led in a more or less straight line 25 in a slightly upwardly inclined direction, while it is subjected to a regulated inflation and any necessary treating liquid is allowed to fall on it during one part of its passage, and washing media, as for example water, allowed to fall on it during a subsequent part of its passage in the 30 slightly upwardly inclined direction. From the annular jet where the tube is formed to the point where the abovementioned washing is effected, the tube travels more or less in a straight line 35 and is not bent once or several times through an angle of between 90° and 180° by passing over one or more rollers as has hitherto been described. We prefer to make use of an annular jet submerged below the surface of the coagulating 40 bath and provided with a central hole through which the coagulating bath enters the inside of the tube at its formation. The tube travels along an inclined path in the bath, so that it soon emerges from the bath and is then led onward, 45 for instance along a trough above which are situated spraying devices through which the treating fluid and the washing media are allowed to fall on the tube. If desired, the tube can be supported by a travelling band during its passage from the coagulating bath to the trough, and even along other parts of its path. The 50 tube is kept regularly inflated during the whole of the time until the washing is completed, and we prefer to effect this by means of a narrower rubber tube passing through the central orifice

of the jet to a point beyond the level of the coagulating bath inside the tube of cellulose or cellulose compound. The back end of the rubber tube is connected with a two-way valve, so that either compressed air or vacuum can be applied to the inside of the cellulose tube. The front end of the rubber tube may be provided with a flanged nipple which raises the end away from the surface of the cellulose tube, in order to prevent the liquid which is draining down the said cellulose tube from entering the rubber tube, and as a rule we prefer to work according to this method; it is, however, possible to arrange that the liquid draining down the cellulose tube should be taken away by means of the said rubber tube 10 which is employed to regulate the pressure inside the cellulose tube, or by means of another similar tube. When commencing to form the tube by projecting the cellulosic solution through the annular jet the end of the tube can be carried by 15 the hand of the workman out of the coagulating bath and along the trough up to the far end thereof, and thence, if desired, through a pair of nip rollers on to a roller for collecting or transporting purposes, and during this period, we 20 prefer to force compressed air into the interior of the cellulose tube to inflate it so that its diameter is about equal to that of the annular jet. After the production of the tube has been 25 in progress for a short time, particularly when viscose is employed as the cellulosic solution, gases are evolved inside the tube so that it becomes necessary to withdraw a certain amount of 30 gas continually from the tube and this is done by applying reduced pressure to the back end 35 of the rubber tube. If desired, the pressure of the gas inside the cellulose tube can be automatically controlled by means of a device which will cause pressure or vacuum to be applied 40 through the rubber tube when the pressure becomes too low or too high respectively. We can also, if desired, treat the inflated cellulose tube while it is still passing along the slightly upwardly inclined path, with other reagents, as for example sodium sulphide solution, bleaching solution 45 and glycerine. In some cases advantages are obtained by carrying out the drying process in addition while the tube is passing along the said slightly upwardly inclined path and is subjected to the regulated inflation, but as a rule we 50 prefer to carry out the drying process separately because it is generally desirable to subject the tube to a greater pressure when drying it, than is used during its formation. It is necessary to 55 make the cellulose tube pass along a slightly up-

wardly inclined path, because the liquid inside the tube then has greater facilities of draining back into the coagulating bath, or being taken away by a rubber control tube as hereinbefore described.

The accompanying drawing illustrates one example of apparatus for carrying out the invention, which, however, is not limited to the example shewn. Figure 1 is a sectional elevation and Figure 2 shews, also in sectional elevation, a part of Figure 1 on a larger scale. Viscose is employed as the cellulosic solution, and this is projected into a coagulating vat containing a solution of an ammonium salt, where the tube is formed, the said tube being subsequently subjected to the action of a fixing liquid containing dilute sulphuric acid. Referring to the drawing, A represents the vat containing the coagulating liquor, the upper level of which is indicated by B. The annular jet C is fed with viscose through the pipe D, while E represents an attachment by which the jet can be raised or lowered. The viscose being supplied under pressure, and preferably fed by a pump to regulate its delivery, emerges through the ring orifice F of the jet C, and coagulates, giving rise to the tube K. The said tube K is drawn in an upwardly inclined direction out of the coagulating liquor over the travelling band G along the trough H, where a spray of fixing liquid falls on to it from the spraying device L. The trough H is provided with a perforated bottom, so that the fixing liquid falls through and collects in the tank M. The tube K, after leaving the trough H, passes along another trough N, where it is sprayed with water by means of the spraying device, the washing water collecting in a tank V. It may be necessary or desirable to employ more than one trough and spraying device so as to effect sufficient washing of the tube and it is also advantageous to carry out a part of the washing process with water at a high temperature or with steam. After the tube has been washed sufficiently, it can be passed through a pair of nip rollers Q, R and then through one or more tanks S containing suitable liquor for after-treatment, as for example sodium sulphide solution, or bleaching solution, or diluted glycerine. We prefer, however, as stated above, to carry out any further treatment with sodium sulphide solution, or bleach solution, or diluted glycerine, while the tube is still passing more or less in a straight line in a slightly upwardly inclined direction, the said treating liquids being sprayed onto the tube from above while making use of troughs and spraying devices similar to those already illustrated at H, N and L, P respectively.

Figure 2 also shews the narrow rubber tube T which passes through the jet C into the interior of the tube K to a point beyond the level B of the coagulating bath. The inner end of the tube T is provided with a flanged nipple U, which raises that end of the tube away from the surface of the cellulose tube. The other end of the tube T is attached to a two-way valve (not shewn) by means of which either pressure or vacuum can be applied to the inside of the cellulose tube.

What we claim is:—

1. Process for the production of tubular bodies from cellulosic solutions comprising the steps of leading the tube after it has left the bath in which it is formed substantially in a straight line and in a slightly upwardly inclined direction, while it is subjected to the action of any necessary treating liquid and to the washing process necessary

to remove the treating liquid and of subjecting the tube to a regulated inflation.

2. Process for the production of tubular bodies from cellulosic solutions comprising the steps of leading the tube after it has left the bath in which it is formed substantially in a straight line and in a slightly upwardly inclined direction, while it is subjected to the action of any necessary treating liquid and to the washing process necessary to remove the treating liquid and also to any additional wet treatment which is necessary or desirable before drying and of subjecting the tube to a regulated inflation. 5

3. Process for the production of tubular bodies from cellulosic solutions comprising the steps of leading the tube after it has left the bath in which it is formed substantially in a straight line and in a slightly upwardly inclined direction, while it is subjected to the action of any necessary treating liquid and to the washing process necessary to remove the treating liquid and of subjecting the tube to a regulated inflation, by means of a pipe passing within the said tube and having its end above the level of the said bath. 15

4. Process for the production of tubular bodies from cellulosic solutions comprising the steps of leading the tube after it has left the bath in which it is formed substantially in a straight line and in a slightly upwardly inclined direction, while it is subjected to the action of any necessary treating liquid and to the washing process necessary to remove the treating liquid and of subjecting the tube to a regulated inflation, by means of a pipe passing within the said tube and having its end above the level of the said bath. 20

5. Apparatus for producing tubular bodies from cellulosic solutions comprising a bath within which the tube is formed, an annular jet within the said bath means for supporting said jet at an acute angle to the surface of said bath, means for moving the tube substantially in a straight line in a slightly upwardly inclined direction, means for subjecting the tube to regulatable inflation and means for applying wet treatment to the tube during said movement. 25

6. Apparatus for producing tubular bodies from cellulosic solutions comprising a bath within which the tube is formed, an annular jet within said bath, means for moving the tube substantially in a straight line in a slightly upwardly inclined direction comprising a travelling belt and a pair of nip rollers, means for subjecting the tube to regulatable inflation comprising a pipe 50 connected through a two-way tap to sources of pressure and vacuum, and means for applying wet treatment to the tube during said movement comprising spraying devices arranged above troughs having perforated bottoms. 30

7. Apparatus for producing tubular bodies from cellulosic solutions comprising a bath within which the tube is formed, an annular jet within the said bath, means for moving the tube substantially in a straight line in a slightly upwardly inclined direction, means for applying wet treatment to the tube during said movement, means for subjecting the tube to regulatable inflation and means for keeping the tube at the same pressure from the point at which it leaves the annular jet to a point at which the evolution of gas inside the tube has practically ceased. 35
